Patented Dec. 13, 1921.

Inventor

D. W. GAGE,

By *Geo. P. Fimmel*
Attorney

UNITED STATES PATENT OFFICE.

DANIEL W. GAGE, OF PRITCHETT, TEXAS.

PLOW.

1,400,429.

Specification of Letters Patent. Patented Dec. 13, 1921.

Application filed June 29, 1920. Serial No. 392,721.

To all whom it may concern:

Be it known that I, DANIEL W. GAGE, a citizen of the United States, residing at Pritchett, in the county of Upshur and State 5 of Texas, have invented certain new and useful Improvements in a Plow, of which the following is a specification.

This invention relates to plows and has for one of its objects to improve the construction and increase the efficiency and utility without material increase of expense 10 or weight.

Another object of the invention is to produce an attachment which may be adapted 15 without material structural change to plows of various forms and whereby the steadiness of the plow is increased and means provided for enabling a person to operate a single stock plow equally as easily as a turning 20 plow.

With these and other objects in view, the invention consists in certain novel features of construction as hereinafter shown and described and then specifically pointed out 25 in the claim, and in the drawings illustrative of the preferred embodiment of the invention.

Figure 1 is a side elevation of a portion of a conventional plow including the beam 30 and standard with the improvement applied.

Fig. 2 is a front elevation of the parts shown in Fig. 1, with the shovel removed and the beam in transverse section.

35 A portion of the beam is represented at 10, and the standard at 11, the latter formed in two portions in spaced relation bearing upon opposite sides of the beam and clamped thereto by bolts 12 and 13 and connected at 40 their lower ends by a foot member 14.

A brace 15 connects the standard to the beam at the rear of the bolts 12 and 13, as shown.

Pivoted at 16 between the standard members is an arm extending rearwardly as at 45 17 and thence downwardly as at 18 and thence again rearwardly as at 19. A wear

or bearing shoe 20 is detachably coupled to the arm at 21.

The normally vertical portion 18 of the 50 arm is supplied with a plurality of perforations 22, and pivoted at 23 in one of these perforations is a link 24. At its upper end the link is formed with a forwardly directed slotted extension 25 through which 55 the clamp bolt 13 passes, as shown.

The shovel is represented at 26 and secured in the usual manner to the beam members by a clamp bolt 27, the shovel not being shown in Fig. 2, as it would obscure the 60 arms 17, 18, 19 and the shoe 20.

By means of this attachment a single stock plow is held as steady as the ordinary turning plow, and the link 24 may be adjusted to allow the plow to run deep or 65 shallow as may be required.

The shoe 20 operates as a "land side" and is the only part subjected to wear and can be readily renewed without discarding the other parts.

70 The preferred embodiment of the invention is disclosed in the drawings and set forth in the specification, but it will be understood that any modifications within the scope of the claim may be made in the construction without departing from the principle of the invention or sacrificing any of its advantages.

What I claim is:

75 In a plow including a shovel supporting standard, an arm formed with an upper substantially horizontal forwardly extending portion pivoted at its forward end to the standard, a lower substantially horizontal rearwardly extending portion carrying a 80 wearing shoe, a substantially vertical portion between the upper and lower portions, a link pivoted at one end to the standard, and means for pivoting the link adjustably at its lower end to the vertical portion of 85 the arm.

90 In testimony whereof, I affix my signature hereto.

DANIEL W. GAGE.
